INVENTOR:

Albert A. Griswold

by Chas. H. Luther

ATTORNEY:

UNITED STATES PATENT OFFICE.

ALBERT ABBE GRISWOLD, OF PROVIDENCE, RHODE ISLAND.

ROLL ROOFING.

Application filed December 3, 1926. Serial No. 152,492.

My invention has reference to an improvement in the means for securing the lower edge portion of roll roofing, to the roofs of buildings.

5 Roll roofing has heretofore been secured to roofs, sidings and the like, by laying it lengthwise of the roof, the lower edge of an upper course overlapping the upper edge of the next lower course of roll roofing. The roll roofing is then secured to the roof or siding by driving nails through it into the roof or siding. The nail holes thus formed in the roll roofing will cause it, sooner or later, to leak, thereby ruining the utility of the roll roofing and the greater portion of all roll roofing. 10 Leaks are caused by nail holes through the roofing material.

15 The object of my invention is to improve the means for securing roll roofing or the like to roofs, thereby eliminating the driving of nails or the like, through the overlapping edge portion of the roll roofing.

20 A further object of my invention is to provide roll roofing with roll roofing fasteners, 25 each fastener being pivotally and permanently secured to the roll roofing and forming an integral part of the roll roofing.

25 Another object of my invention is to simplify the construction of roll roofing fasteners, whereby the cost of such fasteners is reduced to a minimum.

30 My invention consists in the peculiar and novel method and construction of means for fastening roll roofing to roofs and the like, 35 said fastening means having details of construction, as will be more fully set forth hereinafter and claimed.

35 Figure 1 is a top plan view of a section of a roof with portions of my improved roll roofing and illustrating the first step of my improved method of laying roll roofing.

40 Figure 2 is a top plan view similar to Figure 1 and illustrating the second and final step of my improved method of laying roll roofing.

45 Figure 3 is an enlarged detail sectional view taken on line 3, 3, of Figure 1, and looking in the direction of the arrow *a*.

50 Figure 4 is an enlarged detail sectional view similar to Figure 3, taken on line 4, 4, of Figure 1, and looking in the direction of the arrow *b*, and

Figure 5 is an enlarged perspective view of my improved roll roofing fastening member, removed from the roll roofing. 55

In the drawing 6, 6, indicates the roof boards of a roof, 7, 7, my improved roll roofing and 8, 8, my improved roll roofing fasteners, which are permanently secured to the roll roofing adjacent the edge of the roll roofing. The roll roofing 7, 7, has the usual top coating 9, 9, of asphalt or asphalt and ground slate. The roof boards 6, 6, may also represent the sheathing on the outer walls of a building. 60

65 My improved roll roofing fasteners 8, 8, are constructed preferably of sheet metal in the form of an elongated narrow flat member having preferably rounded ends 10 and 11. In the rounded end portion 10 is a nail hole 12 and in the rounded end portion 11 is a rivet slot 13.

70 Each fastening member 8 is movably and permanently secured to the roll roofing, adjacent its lower edge, by a rivet 14, which extends through the slot 13, in the fastening member 8. The inner head of the rivet 14 is embedded in the roll roofing and is covered by the top coating 9 of the roll roofing, as 75 shown in Figures 3 and 4, thereby water proofing the rivets. 80

75 The roll roofing 7, 7, is usually laid lengthwise of the roof, first a narrow strip at the roof edge and then the strips are laid full width, the lower edge portion of each upper course overlapping the upper edge portion of the next lower course, as shown in Figures 2 and 4. 85

80 When my improved roll roofing is put to use the method of the laying the roll roofing 90 is as follows. With the roll roofing fasteners 8, 8, in the position as shown in Figure 1, each fastener 8 is nailed in place by a nail 15, through the nail hole 12. This one nail 15, to each fastener 8, is also driven through the 95 upper edge portion of the next lower course of roll roofing and into the roof boards 6, 6, thereby with one nail, securing the fastening member and the next lower course of roll roofing to the roof. The next upper course of roll roofing 7, now being laid, is then given a 100 downward semi-circular motion in the direction of the arrow *c*, *c*, Figures 1 and 2. When this next upper course of roll roofing has

reached its extreme downward movement, it has lapped over the upper edge portion of the next lower course of roll roofing, thereby giving the required lap to the roll roofing as shown in Figures 2 and 4. The rivet slot 13, in the fasteners 8, 8, allows for expansion and contraction of the roll roofing, or the roof boards. The roll roofing 7, is now firmly secured in place by the fasteners 8, 8, and can not move out of its place on the roof, after the next upper course of roll roofing is nailed in place, through the fasteners 8, 8, as heretofore described.

It is evident that the course of roll roofing being laid could be given a semi-circular downward movement to either the right or left, as desired.

I do not wish to confine myself to the construction of the roll roofing fasteners shown,

as these fasteners could be constructed in various forms, to give the same result.

Having thus described my invention I claim as new:—

In roll roofing construction, a flat elongated metal roll roofing fastener having a rivet slot in one end and a nail hole in the other end, a rivet through the rivet slot in the fastener and extending into the roll roofing and a nail through the nail hole in the fastener into a roof, whereby the roll roofing is secured to the roof and expansion and contraction of the roll roofing or the roof boards is compensated for, by the slot in the fastener.

In testimony whereof, I have signed my name to this specification.

ALBERT ABEE GRISWOLD.
